United States Patent Office.

A. BALDING, OF MEMPHIS, TENNESSEE.

Letters Patent No. 93,794, dated August 17, 1869.

IMPROVEMENT IN PUMPS.

The Schedule referred to in these Letters Patent and making part of the same.

To all whom it may concern:

Be it known that I, A. BALDING, of Memphis, in the county of Shelby, and State of Tennessee, have invented an Improved Submerged Force-Pump; and I do hereby declare that the following is a full and exact description of the same, reference being had to the accompanying drawings, making part of this specification.

Figure 1 is a longitudinal vertical section of the plunger.

Figure 2, a side view of the same.

Like letters of reference designate corresponding parts in both figures.

This plunger is intended to be used in double-acting submerged pumps, in which the rod is hollow, and serves the double purpose of rod and discharge-pipe.

Let A represent a hollow pump-rod, connected by a hollow cubical chamber, B, with a piston, C.

D is a valve, hinged, as shown, to the interior of the chamber B, in such a manner that it closes alternately the induction-ports E and F.

When the up-stroke is made, the valve closes the port E, and the water, reacting against the interior of the pump-chamber, is forced through the port F, and upward through the pipe A, as indicated by the black arrow.

At the down-stroke, the valve closes the port F, and the water passes directly through the port E, and thence upward through the pipe A, as indicated in red lines.

Having thus described my invention,

What I claim as new, and desire to secure by Letters Patent, is—

The pipe A, chamber B, piston C, and valve D, all combined and arranged substantially in the manner shown, to form a double-acting plunger, for the purposes set forth.

Witness my hand, this 27th day of April, 1869.

A. BALDING.
